UNITED STATES PATENT OFFICE.

ALEXANDER McMILLAN, OF CHELAN, WASHINGTON.

BASE-BALL APPARATUS.

1,086,067.

Specification of Letters Patent. Patented Feb. 3, 1914.

Application filed May 15, 1913. Serial No. 767,866.

To all whom it may concern:

Be it known that I, ALEXANDER McMILLAN, a citizen of the United States, and a resident of Chelan, in the county of Chelan and State of Washington, have invented certain new and useful Improvements in Base-Ball Apparatus, of which the following is a full, clear, and exact specification.

This invention relates to apparatus for mechanically pitching a base-ball, and it has for its object to provide a device for automatically returning a base-ball to the batter after it is batted out in batting practice, thus dispensing with the service of fielders as well as pitchers.

Other objects are to provide for always returning the ball to the same point on the field, that is over the plate or place where the batter is standing, and for causing the ball to pass over the plate at different levels.

A further object is to permit the batter to reset the ball discharging means without leaving his place at the plate and while the ball is being automatically brought into position to be discharged or pitched, whereby the batting may be continued without interruption.

The invention will be first hereinafter described in connection with the accompanying drawings, and then set forth more specifically in the claims at the end of the description.

In the accompanying drawings in which similar reference characters are used to indicate the same parts throughout the several views: Figure 1 is a longitudinal vertical sectional view of apparatus constructed in accordance with my invention, parts being shown in elevation; Fig. 2 is a top plan view of said apparatus; Fig. 3 is a detailed view on an enlarged scale of the ball discharging device or "kicker" and its trip, the same being shown in side elevation, Fig. 4 is a front elevation of the same, the lower end of the tube and adjacent portion of the looped track being shown in dotted lines to more clearly illustrate the lateral offset of said discharging device from behind the tube and track. Fig. 5 is a detail side elevation of a modified form of discharging or pitching device, and Fig. 6 is a detail plan view of the free end portion of said device.

Referring more particularly to Figs. 1 to 5 inclusive, of the drawings, A, A designate the sides of an inclosure arranged in front of the plate B and extending a suitable distance longitudinally and vertically. Said sides are preferably curved slightly, as clearly shown in Fig. 2, and may be made of boards, canvas or other suitable material. Arranged between said sides of the inclosure and terminating just beyond or near the ends of the sides farthest from the plate, is an inclined plate C extending the full width of the inclosed space and terminating at the top in a reverse curve c projecting over and adapted to deliver the ball onto a cover D for the inclosure, which cover slopes from all directions to the entrance of a tube E. The inclined or elevating plane and the cover may both be made of canvas suitably stretched and secured. The tube E may be of wood or other suitable material, and of a size to permit the ball to pass readily through it. Said tube is inclined slightly rearward, preferably about one inch horizontally to one foot vertically. At the lower end of the tube there is arranged a looped or segmental track F substantially U-shaped and of about one foot radius. Said looped track has its rear portion offset laterally, as illustrated in Fig. 4, and to said rear portion, so as to form a continuation thereof, is hinged the discharging device or "kicker" G.

The track may consist of a pair of parallel rods f placed about two inches apart and connected together at suitable intervals by bridge members f', Figs. 3 and 4. To one of said bridge members is pivoted a tripping lever H having its upper end extending into the path of the ball as it passes along the track onto the discharging device. The lower end of said tripping lever is attached by a flexible or other connection h to the lower end of an intermediately pivoted locking lever K the upper end of which is bent and hooked to engage and normally retain the discharging device in withdrawn or retracted position in which it is ready to act upon the ball when the locking lever is disengaged by the actuation of the tripping lever as the ball passes onto the discharging device. The discharging device may also be made of two parallel rods g which may be

connected by a bridge member g' carrying the hook g^2 which is normally engaged by the upper end of the locking lever.

- The discharging device or "kicker" is 5 pressed by a strong spring L the tension of which may be regulated by means of a set screw l , see Fig. 3. This spring propels the discharging device toward the plate when the locking lever is swung to released position. The discharging device is reset, that is, it is swung back again into position to be engaged by the locking lever by a treadle M arranged in the plate B and connected by suitable lever m and chain or cable m' to 10 the upper end of said discharging device, said chain or cable having an elastic section or spring m^2 which permits the forward movement of the discharging device, and the locking lever being normally pressed 15 forward into locking position by a spring k . The upper end of the discharging device carries an adjustable member having a plurality of fingers N preferably hinged between the two rods and adjustably held at the desired 20 inclination by any suitable means, such as a clamping bolt n . By loosening said bolt, the inclination of the fingers may be changed, and when tightened, said fingers are locked or clamped in the desired position, whereby the level at which the ball 25 will pass over the plate may be regulated.

From the foregoing it will be readily understood that when the batter bats the ball into the inclosure and it strikes the incline plane C , said ball will travel up said incline and be delivered by the reverse curve e onto the funnel-shaped cover D which will direct it to the pipe or tube E . After passing down said tube, the velocity of the ball will 30 carry the same around the looped track F and up onto the discharging device G . As the ball passes from said track to said discharging device, it will operate the tripping lever H which in turn will swing the locking lever K out of engagement with the hook g^2 on the discharging device, whereupon the spring L will swing said discharging device or lever forward, thereby pitching the ball toward the plate, as indicated 35 by the broken line in Fig. 1. After hitting the ball again and while it is following the course just described, the batter, by simply pressing with his foot on the treadle M , may swing the discharging device back into 40 locked engagement with the locking lever K by means of the lever m and cable or chain m' working in conjunction with the spring k which normally presses said locking lever toward the discharging device, so that by 45 the time the ball reaches said discharging device again it will be reset and ready for again propelling said ball toward the plate.

Referring to Figs. 5 and 6, in which a modified form of pitching device is illus-

trated, E' designates the delivery tube corresponding to the tube E already described. In this instance, the tube may be straight instead of inclined, and the ball may be delivered directly upon the pitching arm G' , at least upon the adjustable fingers N' of said arm, as indicated in Fig. 5, said fingers being adjustable in the same manner as already described in connection with the fingers N , Figs. 1, 2, 3 and 4. The fingers N' may consist of two parallel portions joined at their outer ends by a cross piece n' . A pair of guide arms O may extend upwardly substantially at right angles to the arm G' in order to coöperate with the fingers N' in catching the ball when it drops from the tube, as indicated in dotted lines in Fig. 5. The arm G' is pivoted at g^3 and has a branch g^4 extending to the opposite side of the pivot. The free end of this branch is attached to a spring L' for throwing the 85 pitching arm when the latter is released, as will be presently explained. A turn buckle l' may be provided for adjusting the tension of this spring.

The arm G' is normally held in operative 90 position by a trigger or locking lever K' pressed into engagement with a hook g^5 on said arm by a spring k' . The end of said lever K' projects up through the fingers N' so as to be engaged by the ball as the latter 95 falls onto said fingers. The force of the ball striking said lever K' is sufficient to release it from the hook g^5 , whereupon the arm will swing upward and forward under the action of the spring L' , and throw or 100 pitch the ball forward. In front of the arm there is arranged a lever P , pivoted at g^6 beside the arm G' . The free end of said lever P is connected to a spring R . In its forward movement, the arm G' will strike 105 said lever P and be arrested thereby. The resetting is accomplished by means of the cable or chain m^3 connected at m^4 to a branch p of the lever P which branch extends at the other side of the pivot. The 110 cable or chain m^3 is actuated from the batter's position, as already described in connection with the cable or chain m' .

Having thus described my invention, what I claim as new and desire to secure by Letters Patent of the United States is:

1. A mechanical baseball pitcher comprising means for discharging the ball, of means for guiding a ball onto said discharging means, and tripping means coöperating with 120 said discharging means adapted to be automatically tripped by the ball as it passes to said discharging means.
2. In a mechanical baseball pitcher, the combination of means for discharging the 125 ball, of means for guiding a ball onto said discharging means, tripping means coöperating with said discharging means, adapted

to be automatically tripped as the ball passes onto the discharging means, and means for resetting the discharging means.

3. In a mechanical baseball pitcher, the combination of means for discharging the ball, of means for guiding a batted ball onto said discharging means, tripping means coöperating with said discharging means, adapted to be automatically tripped as the ball passes onto the discharging means, and means for resetting the discharging means from the batter's position.

4. The combination with an inclined plane having a reverse curve at its upper end, of side members inclosing the space in front of said plane, a funnel shaped cover arranged over the inclosure and under the reverse curve of the inclined plane, a baseball discharging device, means for guiding a ball from the base of the funnel shaped cover onto said discharging device, and means adapted to automatically trip said discharging device as the ball passes onto the same.

5. The combination with an inclined plane having a reverse curve at its upper end, of side members inclosing the space in front of said plane, a funnel shaped cover arranged over the inclosure and under the reverse curve of the inclined plane, a baseball discharging device, means for guiding a ball from the base of the funnel shaped cover onto said discharging device, means adapted to automatically trip said discharging device as the ball passes onto the same, and means for resetting said discharging device from the batter's position.

6. The combination with an inclined plane having a reverse curve at its upper end, of side members inclosing the space in front of said plane, a funnel shaped cover arranged over the inclosure and under the reverse curve of the inclined plane, a baseball discharging device, a tube leading from the base of the funnel-shaped cover to a point in front and to one side of said discharging device, a laterally offset track leading from the lower end of the tube to the discharging device and means adapted to automatically trip said discharging device as the ball passes onto the same.

7. The combination in a mechanical baseball pitcher of a discharging device, of means for guiding a batted ball onto said device, said means including a U-shaped track forming a continuation of the discharging device, and a tripping device arranged on the track adjacent the discharging device, whereby the ball, as it passes onto the latter, will automatically release said discharging device.

8. The combination in a mechanical baseball pitcher of a discharging device, of means for guiding a batted ball onto said

device, said means including a U-shaped track forming a continuation of the discharging device, and consisting of a pair of parallel rods connected together by a bridge member, and a tripping device pivoted on said bridge member and extending near to the discharging device, whereby the ball, as it passes onto the latter, will automatically release said discharging device.

9. The combination with a pivoted pitching arm, of fingers on the free end of said arm, and means for varying the inclination of said fingers for regulating the trajectory of the ball.

10. The combination with spring-pressed ball discharging means, of means for guiding a batted ball onto said discharging means, tripping means adapted to release said discharging means as the ball passes onto the same, and means for resetting said discharging means, including a treadle arranged in the ground at the batter's position, a lever operated by said treadle, a flexible connection from said lever to the discharging means, and a resilient section in said connection.

11. The combination with spring pressed ball discharging means, of means for guiding a batted ball onto said discharging means, tripping means adapted to release said discharging means as the ball passes onto the same, and means for resetting said discharging means including a treadle arranged in the ground, and a flexible connection from said lever to the discharging means.

12. The combination with a pivoted pitching arm of a spring for actuating said arm, a locking lever adapted to interlock with said arm to normally hold the arm in retracted position, and means for delivering a ball onto the arm so that it will engage said lever and automatically release the arm.

13. The combination with a pivoted pitching arm, of a spring for actuating said arm, adjustable fingers on the end of the arm, a locking lever projecting through said fingers and adapted to normally hold the arm in retracted position, and means for delivering a ball directly onto said fingers so as to engage said lever for automatically releasing the arm.

14. The combination with a pivoted pitching arm, of a spring for actuating said arm, adjustable fingers on the end of the arm, a locking lever projecting through said fingers and adapted to normally hold the arm in retracted position, guides on the arm for directing a ball onto said lever, and means for delivering a ball onto said fingers, guides and lever.

15. The combination with a pivoted pitching arm, of a spring for actuating said arm, means for normally locking said arm

in retracted position, means for automatically releasing the arm when a ball is placed thereon, a pivoted lever arranged and adapted to move in the path of the arm, 5 means attached to said lever for resetting the arm, and resilient means connected to said pivoted member for returning the lever to normal position after the resetting operation.

In testimony whereof I have signed my name to this specification in the presence of two attesting witnesses.

ALEXANDER McMILLAN.
